UNITED STATES PATENT OFFICE.

OSCAR JOHNSON, OF CHICAGO, ILLINOIS.

LOCOMOTIVE-TENDER.

1,027,852.

Specification of Letters Patent. Patented May 28, 1912.

Application filed November 11, 1911. Serial No. 659,680.

To all whom it may concern:

Be it known that I, OSCAR JOHNSON, a citizen of the United States, residing at Chicago, in the county of Cook and State of Illinois, have invented certain new and useful Improvements in Locomotive-Tenders, of which the following is a specification.

This invention relates to improvements upon the form of tender shown in United States Letters Patent No. 675,795, issued to Edward Ryan and myself on June 4, 1901.

One of the objects of the present invention is to provide means for preventing coal from getting between the hopper or hinged section of the coal-pit and the rear and side walls of the tender, and to accomplish this result without increasing the width of the tender over all, and thus decreasing its clearance.

Another object of the invention is to provide means for holding the side walls of the hopper in proper relation to the side walls of the tender body.

In the accompanying drawings, Figure 1 is a side elevation of a locomotive tender embodying the features of my invention. Fig. 2 is a sectional view taken in the plane of dotted line 2 2 of Fig. 1, but showing the far side of the tender. Fig. 3 is a section on line 3 3 of Fig. 1. Fig. 4 is a fragmental top plan view of the tender. Figs. 5 and 6 are detail views of one of the hinges for the movable section of the coal-pit.

In the form in which I have herein shown my invention the body of the tender comprises side walls 1 and 2, between which, at the forward end of the body is the coal pit, the rear wall of the coal-pit being herein shown as consisting of a forwardly and downwardly inclined plate 3. The floor of the coal-pit is indicated at 4.

The hopper or movable section of the coal-pit consists of a back plate 5 and two side plates 6 and 7 rigidly secured together in any suitable manner, and, if desired, strengthened in any preferred way, as by means of angle-irons 8. The rear end of the back plate 5 may be curved upwardly, as shown in Fig. 1. The forward end of the hopper is pivotally connected to the tender body in any suitable manner, but preferably as shown in Figs. 4, 5 and 6. As therein shown, a suitable number of hinge-members 9 carrying pintles 10 are fixed to the wall 3. Upon the lower edge of the back plate 5 are secured hinge-members 11 having elongated openings 12 therein through which the pintles 10 extend. It will be seen that if, by any possibility, a fragment of coal should get between the inclined plate 3 and the back plate 5, undue stress upon or breakage of the hinges will be obviated, since the hinge-members 11 can move upwardly with relation to the hinge-members 9 to the extent permitted by the elongation of the openings 12.

13, 14 and 15 are transverse strips secured upon the inclined plate 3 and serving to support the back plate 5 at a slight distance from said inclined plate.

In order to prevent coal from dropping behind the hopper, I provide suitable means such as a vertical guard plate 16 secured to the tender body rearwardly of the rear end of the hopper, and to the rear end of said hopper I secure an angle iron 17 with its horizontal flange projecting rearwardly and overhanging the upper edge of the guard plate 16. If desired, the upper edge of the guard plate 16 may be arched as indicated in Figs. 1 and 3, in which event the angle iron 17 would be correspondingly curved. As a further means to prevent coal from dropping into the space between the back plate 5 and the inclined plate 3 I provide a guard plate 18 fixed in the tender body near the upper edge of said guard plate lying close to the back plate 5 when the hopper is in its lower position.

In order to exclude coal from the space between each side of the hopper and the adjacent side wall of the tender body, I provide upon the tender body a guard flange 19 which may, if desired, be a portion of a Z-bar 20, the Z-bar being fixed by one of its flanges to the side wall of the tender body. In order not to increase the width over all of the tender, the Z-bar is preferably placed upon the inner side of the walls 1 and 2, as shown in Fig. 3. Upon each of the side walls 6 and 7 of the hopper is fixed a co-operating guard flange 21 which may also be a part of a Z-bar 22 secured upon the outer side of the hopper-wall in position to overhang the guard flange 19 when the hopper is in its lower position.

By reason of the location of the guard flange 19 upon the inner side of the tender wall, the adjacent side wall of the hopper is spaced away from the tender wall; and in order to close this space at the forward side of the hopper, I provide upon the in-

ner side of each of the side walls of the tender body, a chafing box which may be of any suitable construction, but which preferably comprises a segmental plate 23 and two filler pieces 24 lying between the plate 23 and the tender wall. As shown in Figs. 2 and 4 the forward edges of the side walls 6 and 7 of the hopper lie close to the plates 23. As shown in Fig. 1, the chafing boxes 10 extend forwardly from the hopper when the latter is in its lower position.

In order to prevent the side walls of the hopper from moving inwardly away from the side walls of the tender body, I provide 15 on each tender wall a guide or retaining flange which is conveniently formed by extending the plate 23 upwardly, as shown in Fig. 3, said extension being reinforced by attaching one or more plates 25 thereto. 20 The upper edge of said guide flange is curved upon the arc of a circle having as its center the axis of the hopper. 26 is a filler block fixed to the forward end of the Z-bar 22 upon the hopper (and upon the 25 inner side of said Z-bar) to lie at the outer side of the guide flange formed by the plates 23 and 25. It will be seen that said guide flange, acting in conjunction with the Z-bar 22, holds the side wall of the hopper in 30 operative relation to the side wall of the tender body.

The hopper may be tilted by any suitable means, as for example, that fully described in the before mentioned Letters Patent. I 35 have deemed it unnecessary to illustrate such means in detail herein, an actuating cylinder, however, being represented at 27, and 28 being a rod attached at one end to the hopper and at its other end to a piston 40 in the cylinder. Steam may be admitted into the cylinder below the piston through a pipe 29 connected to the locomotive boiler.

In use, the forward open end of the coal pit is closed by any suitable means, such as 45 the ordinary removable gate (not shown) until all of the coal readily accessible has been removed, whereupon the fireman removes the gate. Steam may then be admitted to the cylinder 27 to tilt the hopper 50 forwardly a slight distance in order to cause the coal lying in said hopper to slide forwardly into convenient reach of the fireman. The hopper 5 may thus be tilted forwardly farther and farther each time until 55 all of the coal has been deposited within the fireman's reach.

When the coal pit is being filled, the hopper is in its lower position, as shown in full lines in Fig. 1, at which time the guard 60 members 16, 17, 20 and 22 prevent coal from dropping into the space between the hopper and the adjacent parts of the tender body. While the hopper is being tilted forwardly the chafing boxes and the guard members 65 22 and 25 prevent coal from working in

between the side walls of the hopper and the side walls of the tender.

I claim as my invention:

1. A locomotive tender comprising a body having a coal-pit, a hopper pivoted in said coil-pit, said hopper having a rear wall and two side walls, guard means on the inner sides of the tender body, chafing boxes located on the inner sides of the tender-body close to the sides of the hopper, guard means on the sides of the hopper overlying the guard means on the tender body, and means for operating said hopper. 75

2. A locomotive tender comprising a body having a coal-pit, a hopper pivoted in said coal-pit, said hopper having a rear wall and two side walls, chafing boxes located on the inner sides of the tender body close to the sides of the hopper and extending forwardly from the hopper when the latter is in its lower position, and means for operating said hopper. 80

3. A locomotive tender comprising a body having a coal-pit, a hopper pivoted in said coal-pit, said hopper having a rear wall and two side walls, chafing boxes located on the inner sides of the tender body close to the sides of the hopper and extending forwardly from the hopper when the latter is in its lower position, guard means on the inner sides of the tender-body rearwardly of the chafing boxes, retaining flanges above the chafing boxes, said flanges being curved on the arc of a circle concentric with the axis of the hopper, a transverse guard means 100 on the tender body at the rear of the coal-pit, guard means on the rear and side walls of the hopper arranged to overhang the several guard means and flanges on the tender body, and means for operating said 105 hopper.

4. A locomotive tender comprising a body, a hopper pivoted to said body, said hopper having a rear wall and two side walls, a Z-bar fixed on the inner side of each side 110 wall of the tender body, and a Z-bar on the outer side of each side wall of the hopper overhanging the Z-bars on the tender-body.

5. A locomotive tender comprising a body, 115 a hopper pivoted to said body, said hopper having a rear wall and two side walls, chafing boxes located on the inner sides of the tender body close to the sides of the hopper and extending forwardly from the 120 hopper when the latter is in its lower position, guard means on the inner sides of the tender-body rearwardly of the chafing boxes, retaining flanges above the chafing boxes, said flanges being curved on the arc 125 of a circle concentric with the axis of the hopper, a Z-bar on each side wall of the hopper arranged to overhang the guard means and retaining flanges on the tender body, and means for operating said hopper. 130

6. A locomotive tender comprising a body, a hopper hinged to the body, said hopper having rear and side walls, and means for retaining the side walls of the hopper in operative relation to the tender body.

7. A locomotive tender comprising a body, a hopper hinged to the body, said hopper having rear and side walls, and means for retaining the side walls of the hopper in operative relation to the tender body, said

means comprising a flange on the upper edge of the side walls of the tender body, and a coöperating flange on the side walls of the hopper.

In testimony whereof I affix my signature in the presence of two witnesses.

OSCAR JOHNSON.
